DESIGN FOR A PLASTIC UNIT FOR USE ON HANDBAGS OR THE LIKE

Irwin M. Robbins, New York, N. Y.

Application August 11, 1944, Serial No. 114,840

Term of patent 7 years

(Cl. D87—3)

To all whom it may concern:

Be it known that I, Irwin M. Robbins, a citizen of the United States of America, residing in New York city, county of New York, and State of New York, have invented a new, original, and ornamental Design for a Plastic Unit for use on Hand bags or the like, of which the following is a specification, reference being had to the accompanying drawing, forming part thereof, wherein,

Figure 1 is a plan view of a plastic unit for use on handbags or the like, showing my new design.

The opposite sides of the design, as shown in Figures 2 and 3, are identical in appearance to the design shown in said views.

The lines forming the border design in Fig. 1 represent parallel grooves and the lines forming the cross hatching in the center of the same figure also represent grooves arranged as shown.

I claim:

The ornamental design for a plastic unit for use on handbags or the like, substantially as shown and described.

IRWIN M. ROBBINS.
